UNITED STATES PATENT OFFICE

THEODORE BOSSARD, OF SALT LAKE CITY, UTAH

CARBURETOR

Application filed July 8, 1929. Serial No. 376,826.

My invention relates to automobiles and more particularly to fueling systems for introducing the fuel to the motor from the gasoline tank.

A further object is to provide a device which when used in combination with my fueling system, filed in the Patent Office, Serial No. 270,231, filed April 16, 1928, will vaporize the fuel after it has been taken from the tank, and introduce it to the engine in a gaseous state.

These objects I accomplish with the device illustrated in the accompanying drawings in which similar numerals and letters of reference indicate like parts throughout the several views, and as described in the specification forming a part of this application, and pointed out in the appended claims.

In the drawings in which I have shown the best and most preferred manner of building my invention Figure 1 is a diagrammatic view of the installation of the device on the intake manifold of an engine with the lead pipes from the fuel supply tank shown, parts cut away. Figure 2 is a side elevation of the device. Figure 3 is a longitudinal vertical section of the device.

In the drawings I have shown the casing of my invention as A, the intake manifold as B, the spring control chamber as C, the motor as D, the exhaust pipe as E, and the fuel tank as G. In the top of the fuel tank I provide my vaporizing device H, as illustrated in my former application Serial No. 270,231 which matured to Patent 1,753,199 issued April 8, 1930, and the connection which joins the main surrounding heater pipe with the exhaust pipe is shown as F.

The casing A of my device is made in a right angle, with a portion A1 at right angles to the main body, and through which the air for the carburetion is introduced. The bottom portion of the device is open at A2 and a closure plate 1 is secured thereto by suitable means, said plate completely covering said opening. On the bottom side of the plate 1, I provide two converging bosses 2 and 3, with the boss 2 of smaller diameter than the boss 3. The said boss 2 is connected with a lead pipe 2b which in turn leads di-

rectly from the fuel in the tank and supplies the rich mixture for idling of the engine. The boss 3 is connected with the tank with a lead pipe 3b and supplies the running fuel to the engine. The boss 3 is hollow at 3a and a control needle valve 5 is carried in a boss 4 formed on the under side of the boss 3, said valve to control the amount of fuel allowed to pass through the opening 3a into the stand pipe 6. The said opening 2a of the boss 2 is partially closed and the opening therein is controlled by a needle valve 11, thereby providing external means of controlling the flow of fuel through the idling pipe and the fuel supply pipe. A stand pipe 6 is formed integral with the plate 1, on the top side thereof, and is bifurcated into a pipe 8 and a branch pipe 9. The said pipe 8 is passed up through the main body of the casing A and a partial closure boss 7 is secured across the said casing, having a hole 7a therethrough, through which the top end of the pipe 8 protrudes. The end of the pipe 9 is carried up along the side of the casing sufficient distance to clear the outer end of a flap valve 13. An idling pipe 10 is connected with the top side of the plate 1, over the end of the opening 2a, and leads up alongside of the pipe 9 to a point just below the valve 13, at which point the idling pipe 10 is passed through one side of the pipe 9 and out through the top open end thereof and said idling pipe is extended up into the intake manifold B to a point 10a above the level of the throttle valve 12. The throttle valve 12 is pivoted in the intake manifold by the pivot pin 12a and a small opening is cut in one side to allow the end 10a of the pipe 10 to be passed therethrough. This construction provides an idling pipe uncontrolled by either flap valve or by the throttle valve so that fuel is introduced into the engine through this idling pipe at all times when the engine is idling.

The flap valve 13 is pivoted within the main casing A by a pin 13a and when the valve is closed it completely closes the entire opening of the casing A other than that space which has previously been closed by the closure 7 with a cut made in the outer end of the said valve through which the pipe 9 is 100

passed. On the back side of the valve 13 I provide spaced apart bosses 14 through which a pivot pin is passed to secure a connecting rod 16 thereto. The other end of the connecting rod 16 is formed into a ball and said ball fits into a ball socket formed in one end of a piston 18.

The spring control chamber C of my invention is formed radially from the main body casing A and at an angle thereto and said chamber is internally threaded to receive a cylindrical piston chamber 17 which chamber is hollow to receive the said piston 18. The free end of the said piston is hollowed out to receive one end of a spring 19 which spring is carried between the piston and the closed end of the chamber 17, and the pressure of the spring is down upon the piston at all times with the tension to close the flap valve 13 in the casing A. A hole 20 is bored through the end of the piston 18 adjacent the socket and connecting the socket with the chamber in which the spring is carried and a plate 21 is pressed into the said piston to hold the ball on the end of the connecting rod 16 into the piston socket. The hole 20 is to provide a valve action on the air contained in the chamber between the head of the chamber 17 and the piston 18 so that when the piston is traveling up the chamber, air is compressed thereabove, and when the piston is traveling down, the ball on the end of the connecting rod is moved slightly away from the said hole 20 allowing the air to pass therethrough to prevent creation of suction or vacuum within the piston chamber. The outer side of the chamber C is provided with a boss to which a spring 22 is secured by a screw 23. The free end of the spring 22 is provided with a pressed dog 24 therein, said dog adapted to fit into notches or teeth 25, which teeth 25 are formed on the outer periphery of the chamber 17. This allows for rotation of the chamber to vary the tension of the spring 19 and for means of locking the chamber from rotation so that it will not change its position except by manual operation for different adjustment of the spring tension.

A choke valve 28 is pivoted in the portion A1 of the main casing A by a pin 29 and is to control the flow of air therethrough, and for starting the motor when it is cold. A lever 29a is secured on the end of the pin 29 and a choke rod 30 is secured in the end thereof by a pin 31.

The throttle valve 12 is controlled by a lever 32 secured on the outer end of the pin 12a and a throttle rod 33 is provided to control the movement of the valve 12.

The operation of my device is as follows:

The idling gasoline vapor is drawn from the tank through the line 2b, the opening 2a, passing through the pipe 10, around the valve 11, and out through the end 10a of the

pipe 10 into the intake manifold of the engine. To start the engine the choke lever 30 is operated closing the valve 28 and as the motor starts the choke may be opened as desired. The running fuel vapors for the engine are drawn from the tank through the line 3b, the opening 3a in the boss 3, around the valve 5, and up through the pipe 6. Part of the vapors are drawn through the opening end 8 and part through the pipe 9 with both pipes being above the valve 13, the air which is allowed to pass the valve 13, will thoroughly mix with the vapors providing complete mixing of the fuel with the necessary amount of air required for complete combustion of the fuel after it has been introduced into the motor. As the motor is accelerated by opening the throttle valve 12 the suction of the motor will draw more fuel vapors through the pipe 3a, and the flap valve 13 will be drawn open commensurate with the suction of the engine allowing just the correct amount of air to enter the upper portion of the casing A where it is mixed with the fuel vapors after they have been drawn out through the pipes 8 and 9. The positions of the pipe 8 and 9 being on opposite sides of the casing A, provides more complete mixing of the fuels before they are drawn into the intake manifold and thence to the engine. This type of device shown is for using vapors as obtained from the tank by any suitable method, but it will be obvious that the carburetor would work if the pipes 3b and 2b were carrying liquid fuels instead of vapors and were connected directly with a float chamber such as would be necessary were the fuels supplied to the pipes from a vacuum tank or fuel pump.

Having thus described my invention I desire to secure by Letters Patent and claim:—

In a fuel mixing device the combination of a casing having an air inlet at right angles thereto; means to manually close said inlet as desired; a plate on the bottom of said casing having two pipes extending upwardly therefrom one of which is bifurcated with one end bent toward the perimeter of the bore and extended upward to near the top end of the casing and with the short end extended up through a hole in a partial closure in said casing; a throttle valve above said casing in the intake manifold with the smaller of the two pipes extended up through a cut in the throttle valve; a flap valve pivoted across said casing adjacent said partial closure; an opening in said flap valve to allow one leg of the bifurcated pipe to pass therethrough; a connecting rod pivoted on the side of said flap valve; a piston secured on the free end of said rod by a ball and socket joint having some degree of play therein; an adjustable cylinder in which said piston is operated, said cylinder being screwed into a control chamber on one side of said casing; 130

a spring between the inner end of the cylinder and the top end of the said piston; and a port through said piston back of the ball and socket joint with the ball end of the connecting rod adapted to close the port when the flap valve is drawn suddenly open and to allow passage of air therearound when the flap valve is closing or moving gradually.

5 In testimony whereof he has affixed his signature.

10 THEODORE BOSSARD.
